FLASK HOLDER

Carl N. Bean, 2510 Vanderbilt Ave., Raleigh, N.C.

Filed Oct. 29, 1963, Ser. No. 77,202

Term of patent 14 years

(Cl. D58—26)

FIG. 1

FIG. 2

The characteristic features of my design reside in the combination, on the flask holder disclosed, of the unitary supporting arms struck out in part from the disc-like base, substantially as shown.

I claim:

The ornamental design for a flask holder, as shown and described.
